ELECTROMAGNETIC POWER MECHANISM

George H. Leland, Dayton, Ohio, assignor to G. H. Leland, Inc., Dayton, Ohio, a corporation of Ohio

Application May 18, 1948, Serial No. 27,796

7 Claims. (Cl. 185—40)

1

This invention relates to an electromagnetic power mechanism, and more particularly to such a mechanism in which the magnet armature has both axial movement and rotary movement, as shown in my applications Serial Number 542,188, filed June 26, 1944, now Patent No. 2,496,880, February 7, 1950, and Serial Number 760,029, filed July 10, 1947, now Patent No. 2,501,950, March 28, 1950.

In the mechanisms illustrated in said applications operative movement is imparted to the power transmitting element by the rotation of the armature when the magnet is energized. The magnet is deenergized at the end of each operative movement of the transmitting element and the transmitting element and the armature are automatically restored to their initial positions and the magnet again energized. Such a mechanism is entirely satisfactory for most purposes but in some installations it is preferable that the power shall be delivered to the part to be operated while the magnet is deenergized.

One object of the invention is to provide such an electromagnetic mechanism in which the power generated by the energization of the magnet will be stored until the magnet is deenergized and then delivered to the device to be operated.

A further object of the invention is to provide such a mechanism in which the power may be stored without loss of power and without decrease in the rapidity with which successive operations are effected.

A further object of the invention is to provide such a mechanism in which the power transmitting element will not be adversely affected by the axial movement of the armature.

A further object of the invention is to provide such a magnet in which the power transmitting or driving element is in the nature of a pawl actuated by the rotary movement of the armature and so mounted as to compensate for the axial movement of the armature.

Other objects of the invention may appear as the mechanism is described in detail.

In the accompanying drawings Fig. 1 is a side elevation of a mechanism embodying the invention; Fig. 2 is a section taken centrally through the magnet of Fig. 1; Fig. 3 is a detail section taken on the line 3—3 of Fig. 2; Fig. 4 is a section taken on the line 4—4 of Fig. 1 showing the mechanism in its normal or inoperative position; Fig. 5 is a similar section showing the parts in the position which they occupy at the end of the operative movement of the armature; Fig. 6 is a section taken on the line 6—6 of Fig. 1 and show-

ing the power transmitting element in the position it occupies prior to the energization of the magnet; Fig. 7 is a similar view showing the power transmitting element in the position to which it is moved by the magnet; Fig. 8 is an enlarged fragmentary view, partly in section, of the switching mechanism of Fig. 5; and Fig. 9 in a detail, partly in section, of the connection between the power transmitting element and its supporting member.

In these drawings I have illustrated a preferred embodiment of the invention and have shown the same in connection with a rotary solenoid of the type shown and described in the above mentioned applications, but it is to be understood that the mechanism as a whole, as well as the several parts thereof, may take various forms without departing from the spirit of the invention.

In the arrangement here shown the rotary solenoid comprises a casing 10 including a back wall 11, a core 12 and a front wall 13. A bearing 14 extends through the back wall and the core in alignment with an axial opening 15 in the front wall. Mounted in the bearing for both axial movement and longitudinal movement is a shaft 16 which preferably extends through the opening 15. Rigidly secured to this shaft is an armature 17 which is here shown as located in the opening 15 in the front wall. Rigidly secured to the armature and to the shaft is a plate 18 the marginal portion of which extends radially beyond the armature in spaced relation to the front wall 13 of the casing. The opposed surfaces of the plate and casing are provided with opposed pairs of oppositely inclined surfaces and preferably these surfaces constitute the bases, or bottom walls of arcuate grooves 19 and 20 in the front wall 13 and the plate 18, as best shown in Fig. 3. Mounted between the inclined surfaces of each pair of such surfaces is an anti-friction element, such as a ball 21, which when subjected to pressure by the plate will move lengthwise of the grooves and thereby cause the plate to rotate. A magnetizing element 22, mounted in the casing about the core, when energized will cause the armature to move axially toward the core and this axial movement will be converted into rotary movement by the action of the balls on the inclined surfaces of the plate and the casing, as fully set forth in the above mentioned applications.

The rotation of the armature may be utilized in various ways to impart movement to a device to be operated. In the present arrangement the device to be operated includes a ratchet wheel

23 secured to a shaft 24 rotatably mounted in a frame member 25 on which the solenoid is supported and which is spaced from the rear or inner side of the solenoid. The ratchet wheel is preferably located on the inner side of the frame member and is rotatable about the axis of the armature shaft 16. Secured to the armature shaft for movement therewith is a power transmitting device which includes a supporting member 26, on which is mounted a transmitting element here shown as a pawl 27, the pawl being carried by an arm 28 which forms a part of the member 26 and is offset therefrom to support the pawl in the plane of and in operative relation to the ratchet wheel 23. The member 26 is also provided with a second arm 29 with which is connected one end of an expansion spring 30, the other end of which is connected with a fixed support, such as the frame member 25, the arrangement being such that when the magnet is deenergized the spring will move the pawl to and retain the same in its normal or idle position as shown in Fig. 6. When the armature and shaft are rotated by the energization of the magnet the pawl 27 is moved in a reverse direction with relation to the ratchet wheel and rides over the teeth of the ratchet wheel without imparting movement to the latter. This reverse movement of the member 26 and the pawl 27 extends the spring 30 and thus places the same under tension. At the end of a predetermined reverse movement of the pawl the magnet is automatically deenergized, thereby releasing the armature and the member 26 for rotation in an operative direction by the spring 30, that is in a direction in which the pawl will engage a tooth of the ratchet wheel and rotate the latter. Thus the power generated by the magnet merely retracts the power transmitting element or pawl and places the spring under tension, thereby storing in the spring the power generated by the magnet, and when the transmitting element is released by the deenergization of the magnet this power is utilized to impart operative movement to the transmitting element.

Only a slight axial movement of the armature and shaft is necessary to impart the desired rotation thereto but the pawl supporting member 26 being rigid with the shaft moves axially therewith and to prevent any adverse effect of this axial movement on the power transmitting element the latter has been provided with means to compensate for such axial movement. As here shown the pawl is mounted on a pivot pin 31 rigidly secured to the arm 28 and extending across the plane of the ratchet wheel. The axial movement of the member 26 and arm 28 will cause the pivoted end of the pawl to move laterally with the arm and with relation to the ratchet wheel. To prevent the displacement of the nose of the pawl with relation to the ratchet wheel by this lateral movement the pivoted end of the pawl is so mounted on the pivot pin 31 that it may have a slight lateral tilting movement, that is the pivoted end of the pawl may move laterally with relation to the nose of the pawl which is in contact with the ratchet wheel. For this purpose the opening or bearing in the pawl through which the pivot pin extends is of a diameter slightly greater than the diameter of the pivot pin, as shown in Fig. 9, and the pawl is yieldably retained in its normal position by a coil spring 32 mounted about the outer portion of the pivot pin and bearing against the outer surface of the pawl. Preferably the convolutions 33 of the outer

end portion of the coil spring are of such a diameter that they will firmly grip the pivot pin and retain the spring in position thereon. The convolutions of the spring adjacent the pawl are of a diameter greater than the diameter of the pivot pin and of the bearing in the pawl so that the innermost convolution 34 engages the pawl on all sides of the pivot pin and thus offers resistance to the tilting movement thereof and retains the same normally in its proper position with relation to the ratchet wheel. In the present arrangement the spring 32 also serves to urge the nose of the pawl into engagement with the ratchet wheel and for this purpose the innermost convolution 34 is provided with an end portion 35 which extends over the upper edge of the pawl 27 at a point spaced from the axis thereof and thus constantly urges the nose of the pawl toward the ratchet wheel.

20 The magnet is energized and deenergized in accordance with the movements of the power transmitting pawl 27, and for this purpose a normally closed switch is connected in the magnet circuit and means are provided for opening the same when a predetermined reverse movement has been imparted to the pawl 27 by the magnet and for again closing the switch after the pawl has been actuated by the spring 30. As here shown the switch comprises a fixed contact member 36 mounted on the frame member 25, and a movable contact member 37 carried by a resilient arm 38, that end of the arm opposite the contact member being rigidly mounted on the frame member at 39. A normally stationary switch actuating member is mounted on the frame member 25 and operated by a moving part of the mechanism to open and close the switch. As here shown this switch actuating member is in the nature of a plate 40 pivotally mounted on the bearing 41 in which the shaft 24 is mounted. This member is, of course, formed of fiber or other insulating material and is retained on the hub and its movement frictionally resisted by a spring 42 connected at its end with the frame member 25 and having an opening through which the shaft 24 extends. This switch actuating plate is provided with two arms 43 and 44 which are arranged on opposite sides of a part connected with and moving with the pawl supporting member 26. In the present instance the outer end portion of the pivot pin 31 extends between the arms 43 and 44 and those arms are so spaced that when the member 26 and the power transmitting pawl are in the normal positions shown in Fig. 6 the pivot pin, or the coil spring, will be in engagement with the upper arm 43 of the switch actuating plate, as shown in Fig. 4, and the latter will be retained in that position, and the switch 36-37 will remain closed, until the magnet is energized, the initial energization being effected by a master switch, not shown. The upper arm 43 is provided with a head 45 which upon the downward movement of the arm 43 will engage the resilient arm 38 which carries the movable contact 37 and move that contact out of engagement with the fixed contact 36. Preferably the arm 38 is provided adjacent the contact 37 with a projection 46 to be engaged by the head 45 of the arm. When the magnet is energized the rotation of the armature moves the power transmitting member in a reverse direction and causes the pin 31 thereof to engage the lower arm 44, thus moving both the arm 44 and the arm 43 downwardly and causing the head 45 to engage the arm 38 and open the switch, the arm 44 being spaced such

a distance from the normal position of the pivot pin 34 that the magnet circuit will be opened when the armature, and therefore the pawl, has completed a predetermined movement. The opening of the switch, of course, deenergizes the magnet and the spring 30 moves the pawl in power transmitting direction, and as the power transmitting movement of the pawl approaches completion the pivot pin will again engage the upper arm 43 and move the same out of engagement with the resilient arm 38, thereby permitting the switch to close. Inasmuch as the master switch remains closed the closing of the switch 36—37 will again energize the magnet and another cycle of operations will be effected. This cycle of operations can be and usually is repeated with great rapidity and the power transmitting element will continue to rapidly advance the ratchet wheel step by step until the master switch in the magnet circuit is opened.

While I have shown and described one embodiment of my invention I wish it to be understood that I do not desire to be limited to the details thereof as various modifications may occur to a person skilled in the art.

Having now fully described my invention what I claim as new and desire to secure by Letters Patent is:

1. In an electromagnetic mechanism, an electromagnet, an axially movable armature for said magnet, means controlled by the axial movement of said armature for imparting rotary movement thereto, a shaft connected with said armature for rotation therewith, a ratchet wheel supported independently of said shaft for rotation about the axis of the latter, a driving member connected with said shaft for rotation therewith, a pawl for said ratchet wheel carried by said member and movable thereby in a reverse direction with relation to said ratchet wheel when said shaft is rotated by said armature, a spring connected with said member to move said pawl in a direction to rotate said ratchet wheel and adapted to be placed under tension by the movement of said member by said armature, and means controlled by said shaft to deenergize said magnet while said spring is under tension and thus release said member for movement by said spring.

2. In an electromagnetic mechanism, an electromagnet, an axially movable armature for said magnet, means controlled by the axial movement of said armature for imparting rotary movement thereto, a shaft connected with said armature for both axial movement and rotary movement therewith, a ratchet wheel mounted for rotation about the axis of said shaft, a member rigid with said shaft, a pawl mounted on said member for engagement with said ratchet wheel and for movement by said member in an inoperative direction when said shaft is rotated by said armature, said pawl being mounted for lateral tilting movement with relation to said member to compensate for the axial movement of said shaft, spring means connected with said member to move said pawl in an operative direction and adapted to be placed under tension by the movement of said member in said inoperative direction, and means controlled by said shaft for deenergizing said magnet when said pawl has been moved a predetermined distance by said armature.

3. In an electromagnetic mechanism, an electromagnet, an axially movable armature for said magnet, means controlled by the axial movement of said armature for imparting rotary

movement thereto, a shaft connected with said armature for both axial movement and rotary movement, a ratchet wheel mounted for rotation about the axis of said shaft, a member connected with said shaft for rotation thereby in one direction when said shaft is rotated by said armature, spring means to rotate said member in the other direction, a pivot pin on said member, a pawl mounted on said pivot pin to engage and actuate said ratchet wheel and having a limited lateral tilting movement with relation to said pivot pin, means to yieldably resist the tilting movement of said pawl, and means controlled by said shaft to deenergize said magnet when said shaft has been rotated a predetermined distance by said armature.

4. In an electromagnetic mechanism, an electromagnet, an axially movable armature for said magnet, means controlled by the axial movement of said armature for imparting rotary movement thereto, a shaft connected with said armature for both axial movement and rotary movement, a ratchet wheel mounted for rotation about the axis of said shaft, a member connected with said shaft for rotation thereby in one direction when said shaft is rotated by said armature, spring means to rotate said member in the other direction, a pivot pin on said member, a pawl mounted on said pivot pin to engage and actuate said ratchet wheel and having a limited lateral tilting movement with relation to said pivot pin, a coil spring mounted about said pivot pin with its inner end in engagement with said pawl, the convolutions adjacent the outer end of said spring being in gripping engagement with said pivot pin and the convolutions adjacent the inner end of said spring being of an internal diameter greater than the diameter of said pivot pin to yieldably resist tilting of said pawl, and means controlled by said shaft to deenergize said magnet when said shaft has been rotated a predetermined distance by said armature.

5. In a device of the character described an electromagnet, an axially movable armature for said magnet, means controlled by the axial movement of said armature for imparting rotary movement thereto, a member connected to said armature for both rotary movement and axial movement thereby, a ratchet wheel rotatable about the axis of said member, a pivot pin carried by said member, a pawl supported on said pivot pin for movement about the latter and for lateral tilting movement with relation thereto, a coil spring mounted on said pivot pin with its innermost convolution in engagement with said pawl, the outer convolutions of said spring gripping said pivot pin, and the inner convolutions of said spring increasing in diameter progressively toward said pawl, means for deenergizing said magnet as said pawl approaches one limit of its movement, and spring means for moving said pawl to the other limit of its movement.

6. In a device of the character described, a ratchet wheel, a rotatable member supported in axial alignment with said ratchet wheel, means for imparting oscillatory movement to said member, a pivot pin on said member, a pawl for said ratchet wheel mounted on said pivot pin for movement about the axis thereof and for limited lateral movement with relation thereto and a coil spring mounted about said pivot pin on the outer side of said pawl, the convolutions adjacent the outer end of said spring for gripping

engagement with said pivot pin and the convolutions adjacent the inner end of said spring being of greater diameter than said pivot pin, the innermost convolution engaging said pawl to yieldably resist the lateral movement of the latter and having a part engaging said pawl and urging the same toward said ratchet wheel.

7. In a device of the character described, a ratchet wheel, a rotatable member supported in axial alinement with said ratchet wheel, means 10 for imparting oscillatory movement to said member, a pivot pin on said member, a pawl for said ratchet wheel mounted on said pivot pin for movement about the axis thereof and for limited lateral movement with relation thereto, a 15 frustro-conical coil spring mounted about said pivot pin with its outer and smaller end portion in gripping engagement with said pin, and with its larger end portion engaging said pawl to yieldably resist the lateral movement thereof, the 20 innermost convolution of said spring having a

part engaging said pawl at a point spaced from the axis thereof and urging said pawl toward said ratchet wheel.
